T. STOREY,
Shutter Fastener.

No 67,146.

Patented July 23, 1867.

United States Patent Office.

THEOPHILUS STOVER, OF CAMBRIDGEPORT, MASSACHUSETTS.

Letters Patent No. 67,146, dated July 23, 1867.

IMPROVED WINDOW-BLIND FASTENING.

The Schedule referred to in these Letters Patent and making part of the same

TO ALL WHOM IT MAY CONCERN:

Be it known that I, THEOPHILUS STOVER, of Cambridgeport, in the county of Middlesex, and State of Massachusetts, have invented certain new and useful Improvements in Blind-Fastenings; and I do hereby declare that the following is a full, clear, and exact description thereof, reference being had to the accompanying drawings, making a part of this specification, in which—

Figure 1 is an outside view of a portion of a window-blind having my invention applied to it.

Figure 2 is a vertical section through the lower portion of the blind, showing the mode of applying the lifting-rod to the spring-catch.

Figure 3 shows the improved double-catch driven into a vertical joint in brick-work for receiving the latch upon the blind when the latter is thrown open.

Figure 4 is a view of the catch applied to a horizontal joint in the brick-work.

Figure 5 is a view of the pin which holds the spring-latch in place.

Figure 6 is a perspective view of a catch with a grooved shank for wooden buildings.

Figure 7 is a stool-staple for wood-work.

Similar letters of reference indicate corresponding parts in the several figures.

This invention relates to improvements on devices which are designed for holding a window-blind open or shut, as will be hereinafter described.

To enable others skilled in the art to understand my invention, I will describe its construction and operation.

In the accompanying drawings, A represents a portion of a window-blind or shutter, and B represents a strip of spring metal, one end of which is bent and secured fast to the bottom edge of the blind. This strip is so applied that no part of it projects beyond the thickness of the blind, which is very important, for, when otherwise applied, blinds are liable to be broken or badly injured during the process of painting or in transportation. Upon the lower side and at or near the free end of this spring strip the latches a a' are secured by riveting or otherwise. These latches consist of two square studs formed on a piece, a^2 , extending across the spring and secured to it, as stated. The latch a is received by the catch C when the blind is closed, and the latch a' is received by the catch D when the blind is opened. In order to keep the latches and their spring-plate in proper position, and to strengthen the fastening, I employ a stay-pin, E, shown in figs. 1 and 5, which is driven through an oblong hole through the spring B and into the bottom edge of the blind until its shoulder b abuts against the edge of the blind, as shown in fig. 1. The pin E is constructed with a head, b' , against which the spring-latch plate abuts, and the shoulder b is for determining the distance for driving the pin into the blind, so that the latches a a' shall be in a proper plane, with respect to the two catches D and C, to be caught and held by them. Besides serving as a vertical stay for the spring-latch plate this pin E also serves as a lateral support therefor and prevents it from turning about its screw fastening or being strained or bent by shocks. The free end of the spring-plate B is reduced in width and turned up, as shown at B', fig. 2, and to this lip B' a wire rod, g , is suitably attached, which passes up through a hole, h , made vertically through the blind-rail, and also through a plate, i , on top of this rail, and has its upper end bent so as to form a hook for convenience in lifting the latches and their spring-plate. The catch C is constructed with a bevelled or inclined surface, e , for raising the latch as the blind is tightly closed, and it is also constructed with a shoulder, e' , rising from the notch e^2 , for the purpose of serving as a metallic abutment for receiving against it the latch a , as shown in fig. 2. The catch D, which is designed for keeping the blind open when required, may be constructed like the catch C, when used for wooden buildings, but for brick buildings, where this catch is to be driven between the bricks, I construct it as shown in figs. 3 and 4. The catch D is double, that is to say, it has two inclined faces k k' , two notches l l' , for receiving the latch-piece a' , and two shoulder abutments m m' . This construction adapts the catch for being driven into a vertical joint between the bricks of the wall, as shown in fig. 3, and by reversing it it is adapted for being driven into a horizontal joint, as shown in fig. 4. In constructing the shanks or spikes for catches which are to be driven into wood I shall make them as shown in fig. 6. This shank n is fluted or grooved and tapered so as to present a large surface to the wood into which it is driven, and thereby have a firmer hold therein than either a flat or square shank would afford. Such form of shank cannot be twisted or turned in wood very easily, and it can be driven without liability of splitting the wood.

In all my catches, whether for wood-work or masonry, I shall have the shoulder abutments for receiving the shocks in opening or closing the blind, as above described.

Having described my invention, what I claim as new, and desire to secure by Letters Patent, is—

1. The construction of two latches *a a'* upon the spring-plate B, for the purpose of being received and held by notched catches, substantially as described.

2. The pin E, constructed with a head, *b'*, and shoulder or gauge, *b*, upon it, for the purpose of being used in combination with a latch-spring, B, and suitable catching devices, in the construction of a window-fastening, as set forth.

3. The back shoulder abutments upon the catches, when the same are raised higher than the forward shoulders, and prevent the latches passing too far back, as herein set forth.

4. A reversible blind-catch, D, which is adapted for being driven into vertical or horizontal joints between the brick of a wall, substantially as I have explained.

5. The combination of lifting-rod *g* and double-catch or latch-studs *a a'*, with a spring, B, which is applied to the bottom edge of a window-blind and sustained by a pin, E, substantially as described.

THEOPHILUS STOVER.
